WORKPIECE SUPPORTING CRADLE

Filed June 18, 1941

UNITED STATES PATENT OFFICE

2,334,127

WORKPIECE SUPPORTING CRADLE

Arthur Ringzelli, Chicago, Ill.

Application June 18, 1941, Serial No. 398,576

7 Claims. (Cl. 77—63)

This invention relates to improvements in work piece supporting cradles and it consists of the matters hereinafter described and more particularly pointed out in the appended claims.

One of the objects of the invention is to provide a cradle for supporting a piece of work, such as a die, jig or the like, while drilling, counterboring, tapping, milling or grinding the same and which cradle, though simple in construction, is sturdy and is of such weight that it may be readily handled and moved about from one place of use to another.

Another object of the invention is to provide a cradle of this kind, which is rigid in use to assure accuracy of workmanship for the piece supported thereon and at the same time is capable of being readily adjusted into many different positions to meet many requirements as to the work piece to be supported by the cradle.

Also, it is an object of the invention to provide a device of this kind which may be arranged in a folded condition so as to occupy but a little space for storage in periods between uses.

Furthermore, it is an object of the invention to provide a device of this kind, from which chips, filings and small pieces removed from the supported piece of work, and which may lodge upon the supporting surface of the cradle, may be readily removed.

The above mentioned objects of the invention, as well as others, together with the advantages thereof will more fully appear as the specification proceeds.

In the drawing:

Fig. 1 is a perspective view of a work piece supporting cradle embodying the preferred form of the invention, with the parts in one laterally spaced and angularly disposed position.

Fig. 2 is a view of the cradle of Fig. 1 when supporting a piece of work that requires a different spacing and angular disposition between the parts, from that appearing in Fig. 1.

Fig. 3 is a perspective view illustrating certain of the parts of the cradle in a knocked down condition to accommodate a piece of work requiring a further different arrangement of the parts from that shown in Figs. 1 and 2.

Fig. 4 is a horizontal sectional view through the cradle, on an enlarged scale, as taken on the line 4—4 of Fig. 1, when the cradle is in a compact folded condition for storage between periods of use.

Fig. 5 is a detail vertical sectional view on an enlarged scale through a part of the device as taken on the line 5—5 of Fig. 1.

Fig. 6 is a detail vertical sectional view through a corner part of one of the frames of the cradle as taken on the line 6—6 of Fig. 1.

In general, the improved work piece supporting cradle includes a plurality of counterpart frames which generally stand in a upright position and each of which has parallel top and bottom rails or members and posts which operatively connect the top and bottom rails of each frame together at longitudinally spaced points. In connection with said frames there is provided a rigid bar-like means which extend between like members of the frames for holding them rigidly in position. The rigid bar-like means is of such construction and is so connected to said like members of the frames that the frames may be readily adjusted into the desired laterally spaced and angularly disposed relations. As shown herein, the frames are all of the same height and length, but said frames under certain conditions may have different lengths.

Referring now in detail to that embodiment of the invention illustrated in the accompanying drawing, the improved cradle includes a plurality of generally upright, open, rectangular unit-like frames 10—10 and a horizontally extending rigid connecting bar 11. The frames 10—10 in this instance are counterparts having the same height and length, it being more important that said units be the same in height rather than in length.

Each unit-like frame in this instance comprises top and bottom and generally horizontal parallel rails 12 and 13 respectively and a pair of upright connecting posts 14—14 disposed between and connecting the like ends of said rails together. It is preferable that the posts 14—14 of each frame be parallel and they are so herein shown. Each rail 12 and 13, which is herein shown as of a substantially rectangular cross section, has side, upper and lower flat surfaces. In each of said surfaces is one or more longitudinal grooves 15, into which chips, filings and other small parts removed from the work piece supported by the cradle enter for an easy removal. Another advantage afforded by said grooves is that they permit of a better action when said surfaces are being ground.

I prefer to attach the ends of the rails to the ends of the posts by means of set screws 16 as best shown in Fig. 6 so that the top surface of the top rail and the bottom surface of the bottom rail is each a flush surface and devoid of any projecting parts. In the center of the bottom rail is a threaded opening 17 best shown in Fig. 5.

55 The rigid connecting bar is provided with a

central, longitudinally extending slot 18, which extends substantially from end to end thereof, and has a width approximating the diameter of the opening 17 just above mentioned. Preferably, this bar, which also has flat top and bottom surfaces, has a length considerably more than that of the frames 10-10.

The bottom member of each frame has associated therewith, a clamping screw 19 that includes a shank 20 of a diameter to pass through the slot 18 in the connecting bar 11. The bottom end of the shank is screw threaded to match the thread of the opening 17 in the bottom rail of the frame with which it is associated. On the upper end of the shank is a head 21 of a diameter somewhat more than the width of the slot 18 in the connecting bar. This head is knurled externally as shown and is also provided with a transverse opening 22 into which the end of a simple tool may be inserted for turning the screw, clamping tight.

In assembling the cradle, the two frames are disposed in an upright condition and then the bar 11 is inserted through said frames and engaged on the upper surfaces of the rails 13-13. At this time the ends of the bar extend beyond the frames. The bar is disposed with its slot 18 exposing the threaded holes 17 in the rails 13 of both frames. One of the screws 19 is then inserted, threaded end down, through the slot in the bar and into the hole in its associated rail. By turning the knurled heads of the screws by means of the fingers, the heads of said screws can be caused to grip the bar and clamp it reasonably tight to the rails 13-13 of both frames. This holds the frames in an upright position. At this time, the frames may be moved laterally toward or away from one another and may be turned about the axes of the screws 19 into the desired relative angular position required by the piece of work to be operated upon. The frames may then be held in the adjusted position by tightening the screws and whereby the bar 11 is clamped between each lower rail and the head of the associated screw.

In Fig. 2 I have shown a piece of work 23 as supported by the cradle and as engaged at its end portions upon the top surface of the top rails 12-12 of both frames. With the piece of work thus supported, it may be drilled, counterbored, tapped or otherwise worked upon, either by machine or hand, in a very convenient manner. By changing the lateral spacing between the frames and the relative angularity thereof, it is apparent that the cradle may be used to support work pieces of many different shapes and sizes for accurate work thereon.

In some instances, it may be desired to support a work piece 24 in the manner shown in Fig. 3. To so support the work piece, the screws 19 and the bar 11 are removed so that both frames may be disposed upon their sides.

When it is desired to store the cradle during relatively long periods of non-use, it is only necessary to loosen the screws 19 and bring said frames 10-10 together side-by-side with the connecting bar 11 disposed in a slightly angular position with respect to the bottom rails of both frames. The screws 19 may then be tightened to hold the parts in this position, which best appears in Fig. 4.

The device is simple in construction, is sturdy and rigid when set up into operative condition and is easy to manipulate when making the desired adjustment for the work piece to be operat-

ed upon. It is indeed safe in use and has time saving features that are appreciated by tool makers and other skilled mechanics and has many uses around shops where metal and other crafts-
5 men are employed.

While in describing the invention, I have referred in detail to the construction, form and arrangement of the parts involved, the same is to be considered only in the illustrative sense so that I do not wish to be limited thereto except as may be specifically set forth in the appended claims.

I claim as my invention:

1. A work piece supporting cradle embodying 15 therein a plurality of laterally spaced, upright, substantially open frames, each including a top work engageable member and a bottom base member and posts connecting said members together at longitudinally spaced points, rigid means extending between like members of said frames for holding them upright in laterally spaced relation, and means for attaching said rigid means to said like members of said frames, said attaching means being operative to provide 20 adjustment in the lateral spacing between and in the angular relation of said frames.

2. A work piece supporting cradle embodying 25 therein a plurality of laterally spaced, upright, substantially open frames, each including a top work engageable member and a bottom base member and posts connecting said members together at longitudinally spaced points, rigid means extending between the bottom members of said frames for holding them upright in laterally spaced relation, and means for attaching said rigid means to said bottom members of said frames, said attaching means being operative to provide 30 adjustment in the lateral spacing between and in the angular relation of said frames.

3. A work piece supporting cradle embodying 35 therein a plurality of spaced upright substantially open frames, each including a top work engageable member and a bottom base member and posts connecting said members together at longitudinally spaced points, a rigid bar extending between like members of said frames for holding them upright in laterally spaced relation, said bar having a longitudinal slot therein, clamping means extending through a part of said bar and into one of said like members of one frame for pivoting connecting said part of the bar to said one of said like members, and clamping means extending through said slot in said bar into said 40 one of said like members, both of said clamping means being operative to provide adjustment in the lateral spacing between and in the angular relation of said frames.

4. A work piece supporting cradle embodying 45 therein a plurality of spaced upright substantially open frames, each including a top work engageable member and a bottom base member and posts connecting said members together at longitudinally spaced points, a rigid bar extending between like members of said frames for holding them upright in laterally spaced relation, said bar having a longitudinal slot therein, clamping members each extending through said slot in said bar and having a screw threaded engagement at one end in the like members of said frames, said clamping members each having a portion at the other end for clamping engagement with said bars for holding said frames in the laterally and angularly adjusted relation.

5. A work piece supporting cradle embodying 50 therein a plurality of substantially open frames,

each including top and bottom rails and posts connecting said rails together at longitudinally spaced points, the upper surface of the top members of said frames having spaced apart channels therein, rigid means extending between like members of said frames for holding them in laterally spaced relation, and means for attaching said rigid means to like members of said frames, said attaching means being operable to provide adjustment in the lateral spacing between and in the angular relation between said frames.

6. A work piece supporting cradle embodying therein a plurality of laterally spaced upright substantially open frames, each including top and bottom members and posts connecting said members together at longitudinally spaced points, a rigid bar engaged with the upper surface of the bottom members of said frames, and screw threaded clamping members, one for each frame, each clamping member including a part extending through said bar and having a threaded en-

gagement in the bottom member of the associated frame, and each clamping member including an enlarged head for clamping against the upper surface of said bar.

5 7. A work piece supporting cradle embodying therein a plurality of laterally spaced, upright, substantially open frames, each including top and bottom members and posts connecting said members together at longitudinally spaced points, a rigid bar engaged with the upper surface of the bottom members of said frames and which bar has a longitudinal slot therein, and screw threaded clamping members, one for each frame, each clamping member including a part extending through said slot and having a screw threaded engagement in the bottom member of the associated frame and each clamping member including an enlarged head for clamping against the upper surface of said bar.
